UNITED STATES PATENT OFFICE.

WARREN C. FERRIS, OF COLD SPRING, NEW YORK.

NIGHT-LATCH.

1,196,673.

Specification of Letters Patent. Patented Aug. 29, 1916.

Application filed January 12, 1916. Serial No. 71,762.

To all whom it may concern:

Be it known that I, WARREN C. FERRIS, a citizen of the United States, residing at Cold Spring, in the county of Putnam and State of New York, have invented new and useful Improvements in Night-Latches, of which the following is a specification.

This invention relates to locks and latches, and it has particular reference to a night latch of simple and improved construction.

A particular object of the invention is to produce an improved night latch which may not be opened by the introduction between the bolt and the keeper of a flat implement, such as a knife blade, whereby the bolt may be pushed back, as is sometimes done with night latches of ordinary construction.

A further object of the invention is to produce an improved night latch wherein the bolt is combined with a dog whereby the bolt will be positively secured in projected position, means being provided whereby said dog may be released from the inside by a handle member associated with the device and from the outside by a key provided for the purpose.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a top plan view of the improved night latch with parts of the casing broken away and showing the bolt projected. Fig. 2 is a side elevation with the face plate removed and showing the bolt projected. Fig. 3 is a view similar to Fig. 2, but showing the bolt retracted. Fig. 4 is a longitudinal sectional view taken on the line 4—4 in Fig. 3, and showing the bolt retracted. Fig. 5 is a transverse sectional view taken on the line 5—5 in Fig. 2 through the dog engaging cross bar. Fig. 6 is a transverse sectional view taken on the line 6—6 in Fig. 2. Fig. 7 is a perspective detail view showing the bolt and the dog

pivotal connected therewith. Fig. 8 is a perspective detail view of the dog actuating lever. Fig. 9 is a plan view of the arms 44 connected with the barrel 43. Fig. 10 is a view partly in elevation and partly in section, showing a portion of the barrel 43 and related parts.

Corresponding parts in the several figures are denoted by like characters of reference.

The lock case A is provided in the customary manner with a removable face plate 15 which is detachably secured by means of a screw 16 engaging a threaded recess in a post 17. One end wall of the lock case has a slot or opening 18 for the passage of the bolt B; the bottom of the lock case is provided near the end remote from the slotted end wall with a transverse ridge 19 which is intersected by a longitudinal recess 20.

The bolt B is provided with the customary beveled head 21, and it has a bifurcated shank, the limbs of which, 22, are provided with terminal ears or lugs 23, said lugs being connected by pins or pivot members 24 with similar ears or lugs 25 formed on a dog 26 which is adapted to abut on the ridge 19 and which when in this abutting position will resist the retraction of the bolt from its projected position. Rising from the bottom of the lock case adjacent to the ridge 19 are posts 27, said posts being preferably formed of screws that are in threaded engagement with the bottom of the lock case and are provided with heads 28. A cross bar 29 is provided with eyes 30 slidably engaging the posts 27, the cross bar being engaged by springs 31 that are coiled about the posts intermediate the heads thereof and the eyes 30, the cross bar 29 being thereby pressed against the dog 26 which may thereby be retained in engagement with the ridge 19.

To actuate the dog 26 so as to release it from engagement with the ridge 19 and permit the retraction of the bolt there is provided a member which may be called a lever C, the same being shown in Fig. 8 of the drawings, said lever member including in its construction a cross bar 32 having eyes or apertures 33 whereby it engages the posts 27 between the dog 26 and the bottom of the lock case, springs 34 being coiled on the posts 27 between the eyes 30 of the cross bar 29 and the cross bar 32, whereby the last mentioned cross bar is normally forced in the direction of the bottom of the lock

case. The cross bar 32 is provided with V-shaped arms 35 that extend in the direction of the end wall of the lock case which is apertured for the passage of the bolt, said 5 arms terminating clear of the bottom of the lock case, it being important that there shall be sufficient clearance to enable the cross bar 32 to be tilted by pressing the free ends of the V-shaped arms in the direction of the 10 bottom of the lock case. The cross bar 32 is also provided with a tongue 36 that extends beneath the dog 26 in the direction of the slotted end wall of the lock case. The cross bar 32 is finally provided with an 15 arm 37 that extends oppositely to the tongue 36, said arm being positioned in the longitudinal recess 20 of the ridge 19 in the path of a spring actuated push button 38 which extends through the bottom wall of the lock 20 case.

Pivoted in the bottom of the lock case is a turn button 39 having at its outer end a handle 40 and carrying at its inner end a pair of oppositely extending wings or arms 25 having beveled ends that abut on the lugs or ears 23 on the limbs 22 constituting the shank of the bolt B. The inner end of the turn button 39 also has a step 42 forming a bearing for one end of a post or barrel 43, 30 the other end of which has a bearing in the face plate of the lock case. The post or barrel 43 is provided with wings 44 lying adjacent to the wings 41 and also abutting on the lugs 23. The wings 44 are formed by 35 a cross bar which is pivotally connected with the barrel 43 in such a manner as to permit the barrel to make a one-quarter turn without affecting the position of the wings. A turn in excess of a one-quarter revolution 40 will, however, cause the wings to be rotated with the barrel about the axis of the latter. The barrel is provided with radially extending arms 45 which, when the parts are in normal position, will be located at an angle 45 of approximately 90 degrees to the wings 44, said arms 45 being diametrically opposed to each other. The arms 45 are positioned between the face plate of the lock case and the V-shaped arms 35 of the dog actuating lever 50 C so that when said barrel is rotated about its axis, one or the other of the arms 45 will ride on the inclined face of one of the arms 35, thereby tilting the lever member C and causing the dog 26 to be disengaged from 55 the ridge 19.

The bolt B has a longitudinal bore 46 for the reception of a guide rod 47, which latter has an eye 48 engaging the barrel 43. Coiled on the guide rod 47 is a spring 49, 60 whereby the beveled head of the bolt is normally projected beyond the end wall of the lock case.

Secured on the face plate of the lock case is a flat spring 50 that presses against the 65 bolt B for the purpose of maintaining the

latter in proper position and also to assist in preventing the introduction of a tool whereby the bolt might be surreptitiously actuated.

For actuating the improved latch from 70 the outside a key is required which has been conventionally indicated at 51, said key being engaged with the barrel 43, but the manner of its engagement or connection with the barrel constituting no part of the present 75 invention. By means of the key the barrel may be turned about its axis with the result that one of the arms 45 will serve to tilt the lever member C about the fulcrum formed by the terminal of the arm 37, the latter being of sufficient length to produce a degree of movement of the cross bar 32, whereby the dog 26 will be lifted out of engagement with the ridge 19. This result having been accomplished the continued turning of the 80 barrel by means of the key will impart movement to the wings 44, one of which will press against one of the lugs 23 of the bolt, which latter will now be retracted against the tension of the spring 49, the 85 dog 26 sliding unobstructedly over the ridge 19. A stop member 52 is provided which slides in a slot 53 in the lock case, said stop member being capable of being moved into the path of a flange 54 on the bolt B for the 90 purpose of retaining the bolt in retracted position; said stop member, however, may be actuated only from the inside of the door, it being provided exteriorly of the lock case 95 with a handle 55. If the turning movement 100 of the key is discontinued and the key is released without moving the stop member 52 into the path of the bolt, the latter will be automatically projected by the spring 49, thereby restoring the dog in engagement 105 with the ridge 19 where it will be held by the action of the spring actuated cross bar 29; the barrel 43 will likewise be restored to its initial position by the pressure of the lug 23 against one of the wings 44 which is followed by the pressing action of one of the 110 inclined faces of one of the V-shaped arms 35 against one of the arms 45.

To actuate the latch from the inside of the door to which it is applied no key is required, it being only necessary to depress the 115 push button 38 which by engaging the tongue 36 lying in the path thereof will tilt the lever member C about the fulcrum formed by the terminal of the arm 36 thus 120 lifting the dog 26 out of engagement with the ridge 19 and permitting the retraction of the bolt which in this instance is performed by means of the turn button 39 which may be turned in either direction to 125 cause one of the wings 41 to engage one of the lugs 23 formed on the limbs of the bolt member B. By releasing the turn button 39, as well as the push button 38, the bolt 130 will be again shot or projected by the action

of the spring 49 unless the stop member 52 has been previously moved in the path of the flange 54 whereby the bolt will be retained in retracted position. When the door, 5 a portion of which is indicated at D, is swung shut the release of the stop member from engagement with the flange 44 will cause the bolt to be immediately projected by the action of the spring 49 into engagement with the keeper, shown at 56.

It will be seen from the foregoing that the dog 26 constitutes a safety device which positively prevents the retraction of the bolt until the said dog is moved out of engagement with respect to the ridge 15 19.

Having thus described the invention, what is claimed as new, is:—

1. In a latch device, a lock case, a spring 20 projected bolt having a bifurcated shank provided with terminal lugs, a dog having lugs pivotally connected with the lugs of the bolt, and an obstructing member lying in the path of the dog.

25 2. In a latch device, a lock case, a spring projected bolt, a spring actuated dog pivotally connected therewith, an obstructing member in the path of the dog, and means for tilting the dog out of engagement with

30 the obstructing member, said means comprising a lever member including a cross bar having an arm about the terminal of which it may be tilted.

35 3. In a latch device, a lock case, a spring projected bolt, a spring actuated dog pivotally connected therewith, an obstructing member in the path of the dog, and means for tilting the dog out of engagement with the obstructing member, said means comprising a lever member including a cross bar having an arm about the terminal of which it may be tilted, said cross bar being also provided with a tongue extending oppositely to the arm; and a push button engaging the 45 tongue.

40 4. In a latch device, a lock case, a spring projected bolt, a spring actuated dog pivotally connected therewith, an obstructing member located in the path of the dog to 50 maintain the bolt in projected position, and means for disengaging the spring actuated dog from the obstructing member, said means including a lever member having a cross bar, a fulcrum member extending in 55 one direction from said cross bar, a tongue extending in the opposite direction from said cross bar, and V-shaped arms extending from the ends of the cross bar in the direction of that end of the lock case through 60 which the bolt is projected, there being ample clearance between the ends of the V-shaped arms and the bottom of the lock case to permit the lever member to be tilted by pressure exerted on the V-shaped arms.

65 5. In a latch device, a lock case, a spring

projected bolt, a dog pivotally connected therewith, headed posts adjacent to opposite sides of the dog, a cross bar having eyes engaging the posts, and springs coiled on the posts to actuate the cross bar in the direction of the dog. 70

6. In a latch device, a lock case, a spring projected bolt, a dog pivotally connected therewith, headed posts adjacent to opposite sides of the dog, a cross bar having eyes engaging the posts, and springs coiled on the posts to actuate the cross bar in the direction of the dog, said posts having threaded engagement with the lock case. 75

7. In a latch device, a lock case, a spring 80 projected bolt, a dog pivotally connected therewith, posts connected with the lock case adjacent to opposite sides of the dog, a spring actuated cross bar slidable on the posts and engaging the dog, an obstructing 85 member lying in the path of the dog, a tiltable lever member positioned between the dog and the lock case to lift the dog against the action of the spring actuated cross bar out of engagement with the obstructing 90 member, and means for tilting the lever member and for projecting the spring actuated bolt upon the completion of the tilting movement of the lever member.

8. In a latch device, a spring actuated bolt 95 having a bifurcated shank, the limbs of which are provided with terminal lugs, a spring actuated dog having ears pivotally connected with the ears of the shank, an obstructing member lying in the path of the 100 dog to maintain the bolt in a projected position, a dog actuating lever member tiltably arranged between the dog and the bottom member of the lock case, a barrel supported for actual rotation in the lock case between 105 the limbs of the bolt shank, means for tilting the dog actuating lever member, and means associated with the barrel for engaging the lugs on the limbs of the bolt shank to retract the bolt. 110

9. In a latch device, a spring actuated bolt having a bifurcated shank, the limbs of which are provided with terminal lugs, a spring actuated dog having ears pivotally connected with the ears of the shank, an obstructing member lying in the path of the 115 dog to maintain the bolt in a projected position, a dog actuating lever member tiltably arranged between the dog and the bottom member of the lock case, a barrel supported for actual rotation in the lock case between the limbs of the bolt shank, means carried by the barrel for tilting the dog actuating lever member to lift the dog from engagement with the obstructing member, and means also 120 associated with the barrel for engaging the lugs on the limbs of the bolt shank to retract the bolt by continued rotation of the barrel. 125

10. In a latch device, a lock case, a bolt 130

adapted to be projected through one end of the lock case, said bolt having a bifurcated shank, the limbs of which are provided with terminal lugs, a spring actuated dog having lugs pivotally connected with the lugs of the bolt shank, an obstructing member lying in the path of the dog to maintain the bolt in projected position, a tilttable lever member whereby the spring actuated dog may be 5 disengaged from the obstructing member, a barrel supported in the lock case for rotation about its axis, said barrel being positioned between the limbs of the bifurcated bolt shank, a rod on which the bolt is guided, 10 said rod having an eye engaging the barrel and the bolt being provided with a bore for the reception of the rod, a bolt projecting spring coiled on the rod, means for tilting the dog actuating lever member, and means 15 associated with the barrel for retracting the bolt.

20 11. In a latch device, a lock case, a spring projected bolt member, a dog pivotally connected therewith, posts connected with the lock case at opposite sides of the dog, an ob-

structing member lying in the path of the dog, a spring actuated cross bar guided on the posts and engaging the dog to move the latter into engagement with the obstructing member, a tilttable dog actuating lever member including a cross bar having eyes engaging the posts, springs on the posts between the tilttable lever member and the dog actuating cross bar to support the lever member normally in a non-tilted position, means for 25 tilting the lever member to disengage the dog from the obstructing member, and means for retracting the bolt.

20 12. In a latch device, a lock case, a bolt having a longitudinal bore, a key barrel, a guide rod engaging the bore of the bolt and having an eye engaging the key barrel, and a bolt projecting spring coiled about the guide rod.

25 In testimony whereof I affix my signature in presence of two witnesses.

WARREN C. FERRIS.
